UNITED STATES PATENT OFFICE.

FREDERICK K. WRIGHT, OF SYRACUSE, NEW YORK, ASSIGNOR TO THE STEAM GAUGE AND LANTERN COMPANY, OF SAME PLACE.

DESIGN FOR A LANTERN.

SPECIFICATION forming part of Design No. 21,421, dated March 22, 1892.

Application filed February 23, 1892. Serial No. 422,593. Term of patent 14 years.

To all whom it may concern:

Be it known that I, FREDERICK K. WRIGHT, a citizen of the United States, residing at Syracuse, in the county of Onondaga and State 5 of New York, have invented a new Design for Lanterns, of which the following is a specification.

The accompanying drawing is an elevation of a lantern embodying my design.

10 The leading feature of my design consists of a lantern guard or frame in which some of the members have a twisted or rope-like appearance.

15 A represents the bottom of the lantern; B, the lower collar of the frame; C, the vertical

members of the guard or frame, extending upwardly from the collar; D, the horizontal member or ring of the guard or frame; E, the top, and F the globe. The vertical members of the guard or frame have a twisted or rope-like 20 appearance, as clearly shown in the drawing.

What I claim is—

The design for a lantern, as herein shown and described.

Witness my hand this 19th day of February, 1892.

FREDERICK K. WRIGHT.
